COIN CONTROL APPARATUS

William Foy Herschede, Forestville, and William N. Woodruff, Cincinnati, Ohio, assignors, by mesne assignments, to International Vehicular Parking, Ltd., Washington, D. C., a corporation of Delaware

Application November 1, 1938, Serial No. 238,230

8 Claims. (Cl. 194—1)

The present invention relates to a coin control apparatus, such as may be utilized in various types of coin operated, or coin conditioned, mechanisms adapted for various types of service.

An object of the invention is to provide an improved coin control apparatus, wherein many of the faults common to such devices are effectively eliminated.

Another object of the invention is to provide a coin control apparatus of an improved construction for rejecting coins of dimensions other than is intended to be accommodated, and operating so as to maintain a receptive condition of the apparatus associated with the coin control apparatus.

Another object is to provide a novel construction in a coin control apparatus, whereby coins may not be jammed or stuck therein, in such manner as to put out of service the machine or mechanism associated with the coin control apparatus.

Another object is to provide a coin control apparatus, with a novel form of coin shifting well or receiver to ensure perfect alignment of the coin with the coin passageway, thereby obviating stoppages or other conditions tending to impair the services rendered thereby.

A further object of the invention is to provide a device of the character stated, and embodying the meritorious features mentioned, which device is simple of construction and inexpensive to manufacture.

A further object is to provide a coin control apparatus which will indicate the use of spurious coins or slugs therein, regardless of attempts to dislodge such coins or slugs from a position at which they are visible after having been inserted into the apparatus.

The foregoing and other objects are attained by the means described herein and disclosed in the accompanying drawing, in which:

Fig. 1 is an elevational view of a coin operated mechanism, for example a parking meter, showing the device of the invention embodied therein.

Fig. 2 is a front elevational view of a coin control apparatus of the invention.

Fig. 3 is a top plan view of the device disclosed in Fig. 2.

Fig. 4 is a side elevational view taken on line 4—4 of Fig. 2.

Fig. 5 is a view similar to Fig. 2, showing a stoppage of coins such as might occur under certain circumstances, and which will not so affect the improved coin control apparatus as to interfere with continued operation of the meter, or

other device to which the device of the present invention is applied.

In Fig. 1 there is illustrated the casing 8 of a parking meter or any other device to be controlled or operated by the insertion of a coin. The casing is provided with a coin receiving slot 9, which for the purpose of convenience in description, may be just large enough to admit a nickel. It may be assumed throughout this description, that a nickel is a coin of proper dimensions for initiating or controlling the operation of the parking meter or other piece of equipment, it being understood that coins of other dimensions might be accommodated by 10 making a slight alteration in the dimensions of the slot 9 and in the coin control apparatus itself.

The coin control apparatus, identified generally by the character 10, is adapted to be fixed beneath the coin receiving slot 9 in position to accept the coin placed in the slot. A coin so received will drop into the apparatus 10 and will be retained behind a window 12 provided in the casing 8, until such time as another coin is inserted. Upon insertion of the second coin, the first coin will drop into a receptacle 13 provided for the convenience of a collector or service official. Each time that a nickel is inserted in the slot 9, it will operate a means for releasing a previously inserted coin from its position at the window 12.

It is immaterial to the present invention, whether the releasing means be of one kind or another, however, a simple arrangement of bell 35 crank lever indicated at 14 and having a pivotal support 15, will perform the desired function. A coin of proper size will elevate the arm 16, causing the lifter or trip end 17 to engage a trip arm 18 of the coin control apparatus, for releasing 40 of the preceding coin. It should be understood that a slug or coin smaller than a nickel will not trip the lever 14, and that a larger one cannot be inserted into slot 9.

If desired, the element 14 may have suitable 45 connections with the operating mechanism of the parking meter or other device, so as to make the operation thereof dependent upon movement of element 14. Suitable means, not within the purview of the present invention may be employed to prevent tripping of the mechanism without the insertion of any coin.

From the illustration of Fig. 1, it should readily be evident that there is a possibility of the receptacle 13 being filled with coins, to the extent

that coins subsequently fed therein through the coin control apparatus 10 might be precluded from entering the receptacle. According to the present invention, means are provided for properly overcoming the possible ill effects of such a condition, all of which will be explained and treated hereinafter.

The coin control apparatus of the invention (see Figs. 2 and 3) may comprise a front plate 19 and a rear plate 20 maintained in spaced parallelism by means of the lower plate spacers 21 and 22, and the upper plate spacers 23 and 24. The plates are spaced apart sufficiently to receive a nickel therebetween. The plates so related provide an upright coin chute or passageway 25 with both ends open, these forming a coin entrance port 26 and a delivery port 27, the front plate being cut away to expose a coin in the chute to view, through window 12 in casing 8. At opposite sides of the passageway auxiliary exit ports are provided so that, under certain circumstances, coins may be released from the coin passageway without passing through the exit port at the lower end thereof. One of the auxiliary exits, indicated by the character 28, is located between the upper spacer 24 and the lower spacer 22. The other exit, indicated at 29, is located intermediate the upper spacer 23 and the lower spacer 21 at the opposite side of the device. The purpose of the auxiliary exists is to permit lateral delivery or release of a coin which might be dropped into the apparatus while the coin A (see Fig. 2) remains in position behind the window 12. This would occur if a coin of diameter smaller than a nickel were inserted into the slot 9, such smaller coin being incapable of tripping the lever 14-16 to release the previous coin.

It should be understood that the smaller coin, by failing to trip the lever 14-16, could not be effective for operating the parking meter or other device, nor would it effect release of the retained coin A, in which event said smaller coin would merely strike the coin A and roll off to one side or the other through one of the auxiliary exits 28 or 29. A spurious coin or slug of proper dimensions would operate the mechanism, but unless it could be dislodged before reaching the window 12, it would be in full view and detectable as a fraudulent coin.

In the absence of preventive means, it would be possible to drop a spurious coin or slug into the slot 9 for actuating the control lever 14-16, and then, while the spurious coin is passing the auxiliary exits 28 and 29, it would be possible to strike the casing 8 a sharp blow with the object of throwing the spurious coin laterally through one of the auxiliary exits, in which event the spurious coin would be precluded from entering behind the window 12, that is, it would not assume the position of coin A of Fig. 2. To preclude such treatment, however, one of the plates which forms the coin passageway, for example plate 20, may be provided with a pair of wings or extensions 30 and 31, having at their outer ends suitable bumpers 32 and 33 adapted to intercept and throw back, into the passageway, any coin forcibly dislodged from the regular passageway by the action resulting from suddenly jarring the apparatus in a direction transversely of normal coin travel through the passageway. The bumpers may be formed, if desired, by merely turning the outer ends of wings 30 and 31 at an angle, so that a coin projected laterally will strike the bumpers, and will bounce back into the

passageway, where it will show up in the window 12.

The bumpers 32 and 33 preferably are spaced sufficiently from the periphery of a retained coin A, to permit the release, through an auxiliary exit, of any coin dropped into the passageway while a preceding coin such as A remains in the restrained position. Such released coin, if of a proper size will have actuated the control lever 14-16 so that the parking meter or other device will have been actuated. Under normal circumstances, the coin would drop into the position occupied by coin A of Fig. 2 but in the event of choking up of the coin receptacle 13, the coin A might possibly remain at the exit of the device, even though released by the action of the trip 17. It will therefore be understood that failure of the coin to move from its position behind the window 12, will not interfere with proper operation of the parking meter or other coin operated device, although a succession of coins dropped upon the stuck nickel A will not enter the coin receptacle 13.

The release for the restricted coin may be in the form of an escapement pawl (see Figs. 2 and 4), said pawl comprising a lower coin supporting lug 34 and an upper coin interceptor lug 35, said lugs being formed at opposite ends of a connecting piece 36. The interceptor 35 may enter and obstruct the coin passageway, through an opening 37 formed in plate 20. A transverse bar 38 carries the piece 36 and also a trip arm 18 extending diagonally therefrom, and has its opposite ends journaled in suitable bearings as at 39 and 40 (see Fig. 3), so that the entire structure 34-35-36-38 may be rocked upon actuation of the trip arm 18 by means of the trip 17 of Fig. 1.

Fig. 4 clearly discloses the construction of the escapement pawl, and discloses that supporting lug 34 obstructs the coin passageway while the interceptor lug 35 is retracted. Upon upward movement of the trip arm 18, lug 35 intercepts the passageway, and lug 34 is withdrawn to release the coin supported normally thereon. A spring or other suitable means 42 may be employed to yieldingly maintain the coin supporting lug 34 in the extended position for supporting a coin at the delivery port of the coin passageway.

At the entrance port of the passageway, means are provided for shifting a coin into proper position for entry thereof into the passageway. Said means may be referred to as a coin shifting well, and it comprises a pair of arms 43 and 44 extending from the plates which form the body of the device, as disclosed in Fig. 3. Each of the arms has an upper edge 45 and a lower edge 46 (see Fig. 4), said edges diverging from one another so that the lower edges may be in position to contact the periphery of a coin as the coin travels downwardly into the passageway.

Between the arcuate arms 43 and 44, the plates 19 and 20 are cut away at an angle to respectively provide guiding edges 47 and 48 for the coin to slide upon as it gravitates while being guided by the edges 46. The guiding edges 47 and 48 of plates 19 and 20, respectively, are crossed just below the arcuate arms, so as to impart a twist to the coin as it moves downwardly past the arcuate arms. By means of the construction described, the coin may enter the apparatus 10 at right angles to the coin chute or passageway thereof but it will be supported through contact with edges 47 and 48 of plates 19 and 20 and the sloping edges 46 of one or both of arms 43 and 44 against which it will lean and will be turned by

the action of the crossing edges 47 and 48 of the body plates, through a 90° arc so as to enter the passageway proper in parallelism with the planes of the plates. The coin shifting means just described precludes all possibility of a coin lodging cross-wise of the coin passageway during any stage of coin movement after insertion into the slot 9.

Fig. 5 illustrates a condition which might exist in the event that the lower-most coin A becomes stuck or is precluded from entering the receptacle 13 while partly lodged in the passageway, or in the coin delivery port of the apparatus. It should be noted that a coin so lodged may cover the supporting lug 34 and keep it in a depressed condition, while the interceptor lug 35 is extended to obstruct the coin passageway. A second coin B dropped into the apparatus, might leave through the auxiliary exit 28 or it might possibly remain supported upon coin A and spacer 22, as indicated. If the coin B remains within the apparatus as shown, a third coin dropped into the apparatus will necessarily leave through the auxiliary exit 29, and any subsequent coin will do likewise. To insure such operation, it will be necessary that the distance from interceptor lug 35 to bumper 33 be slightly greater than the diameter of a nickel. Also, the distance between said bumper and the upper end of spacer 21 likewise should be slightly in excess of a nickel diameter. Similarly the distance from the other bumper 32 to the spacer 22 should be sufficient to pass a nickel, because if the lower-most coin A were stuck at a slightly higher elevation than indicated in Fig. 5, the coin B would have to leave through the space between 22 and 32. It should be noted that the lower plate spacers 21 and 22 may have slanted or tapered upper ends which may be pointed, if desired, so that a coin may not be balanced thereon and thereby possibly obstruct the auxiliary exits.

Inasmuch as successive coins may be inserted through the coin slot 9 indefinitely, even though there may be a congestion of coins at or below the delivery port of the apparatus, that fact obviously will not affect continued service of the parking meter or other device, but instead, the use thereof may proceed until such time as a service employee calls to remove the congestion or make any repairs that might have been responsible for the failure of coins to normally leave the coin control apparatus. As previously stated, it is immaterial to the present invention as to what form of means might be employed to start the parking meter or other service mechanism after the coin is inserted into the coin slot 9, since the present invention relates chiefly to the coin control apparatus which receives the coin after it has performed the function of starting the parking meter, or whatever type of device the coin is intended to operate.

The characters 50 indicate suitable mounting studs for the coin control apparatus, these serving to support the apparatus in operative position with respect to the casing 8 and its coin slot 9 as well as with respect to the meter and device whose operation is actuated by the coin being handled.

It should readily be understood that obvious changes will adapt the device to operate with coins other than nickels, or suitable tokens may be accommodated, if desired. The fact that a parking meter has been mentioned herein as an example of a mechanism to be associated with the coin control apparatus of this invention, is

not to be considered a limitation upon the many uses or environments in which said apparatus is applicable.

Various modifications and changes in the structural details of the apparatus may be made, within the scope of the appended claims, without departing from the spirit of the invention.

What is claimed is:

1. A coin control apparatus comprising in combination, a front plate and a rear plate arranged in spaced parallelism to accommodate a proper coin, said plates providing a coin passageway open at its ends to form a coin entrance port and a coin delivery port, said passageway being open at its sides to provide a pair of auxiliary exits for coins, means for successively retaining successively inserted coins at the delivery port of the passageway, a pair of wings extending from one of the plates in opposite directions and alongside of the auxiliary exits, and a coin bumper on each wing located remotely from each auxiliary exit at sufficient distance therefrom to be normally out of contact by a coin passing through the passageway but in the path of movement of a coin displaced laterally through an auxiliary exit by jarring the apparatus transversely to the normal coin travel while the coin is in motion through the coin passageway, said bumpers being spaced, from a coin retained in the delivery port, at a distance sufficient to allow a subsequent coin to pass freely between said retained coin and a bumper.

2. A coin control apparatus comprising in combination, a front plate and a rear plate arranged in spaced parallelism to accommodate a proper coin, said plates providing a coin passageway open at its ends to form a coin entrance port and a coin delivery port, said passageway being open at one of its sides to provide an auxiliary exit for coins, means for successively retaining inserted coins one by one at the delivery port of the passageway, a wing extending laterally from one of the plates alongside of the auxiliary exit, and a coin bumper on the wing located remotely from the auxiliary exit at sufficient distance therefrom to be normally out of contact by a coin passing through the passageway but in the path of movement of a coin forcefully displaced laterally through the auxiliary exit by jarring the apparatus transversely to the normal coin travel while said coin is in motion through the coin passageway, said bumper being sufficiently elevated and spaced from a coin retained in the delivery port, to permit free passage of a subsequent coin through the auxiliary exit between the bumper and the retained coin.

3. A coin control apparatus comprising in combination, a front plate and a rear plate arranged in spaced parallelism to accommodate a proper coin, said plates providing a coin passageway open at its ends to form a coin entrance port and a coin delivery port, said passageway being open at one of its sides to provide an auxiliary exit for coins, means for successively retaining inserted coins one by one at the delivery port of the passageway, a wing extending laterally from one of the plates alongside of the auxiliary exit, and a coin bumper on the wing located remotely from the auxiliary exit at sufficient distance therefrom to be normally out of contact by a coin passing through the passageway but in the path of movement of a coin forcefully displaced laterally through the auxiliary exit by jarring the apparatus transversely to the normal coin travel while said coin is in motion through coin

passageway, said bumper being sufficiently elevated and spaced from a coin retained in the delivery port, to permit free passage of a subsequent coin through the auxiliary exit between the bumper and the retained coin, a sloping abutment at one extremity of the auxiliary exit to cause such subsequent coin to roll either through the auxiliary exit or back into the coin passageway, and a second auxiliary exit at the opposite side of the passageway, for release of any coins dropped onto a coin held in the passageway by said sloping abutment.

4. A coin control apparatus comprising in combination, a coin chute body providing a coin passageway open at its ends to provide a coin entrance port and a coin delivery port, and means at the entrance port for rotating a coin into parallelism and alignment with the coin passageway, said means comprising a pair of obliquely disposed guides crossing one another in spaced parallel planes at opposite sides of the coin passageway, and a well for reception of the coin at the crossed guides, comprising a pair of oppositely extended curved arms each having a sloping lower edge to follow a coin in its descent along the crossed guides of the coin rotating means.

5. Coin control apparatus comprising in combination, a coin chute body providing a coin passageway open at its ends to provide a coin entrance port and a coin delivery port and including a straight portion, said body including an auxiliary exit intermediate the straight portion of said body for laterally accommodating coins from the passageway in advance of the delivery port in the event the delivery port is blocked, and a bumper located outside of the passageway and at sufficient distance from the auxiliary exit to be out of contact by a coin passing through the same when the delivery port is blocked but in a position to intercept and throw back into the passageway a coin ejected through the auxiliary exit as by suddenly jarring the apparatus in a direction transversely of the normal direction of coin travel through the passageway.

6. Coin control apparatus comprising in combination, a coin chute body providing a coin passageway open at its ends to provide a coin entrance port and a coin delivery port and including a straight portion, said body including an auxiliary exit intermediate the straight portion for laterally directing coins from the passageway in advance of the delivery port in the event

the delivery port is blocked, and a bumper located outside and remotely from the auxiliary exit at sufficient distance therefrom to be out of contact by a coin passing through the auxiliary exit when the delivery port is blocked but in a position to intercept and throw back into the passageway a coin improperly ejected through the auxiliary exit as by suddenly jarring the apparatus in a direction transversely of the normal direction of the coin through the passageway; and means for retaining the coin in a display position in the passageway at a point beyond the auxiliary exit.

7. In combination, a hollow casing having a coin-receiving slot in one of its sides and an observation window below the slot, a coin receptacle housed within the casing at a point below the window, a coin control apparatus mounted in the casing above the receptacle and between the window and the coin-receiving slot and including a coin-actuated member, means associated with the coin control apparatus for successively retaining in the window area coins successively inserted in the slot, means actuated by inserted coins for releasing the retained coin, and means providing, upon failure of a released coin to move from the window area, a passage for a subsequent coin from the coin control apparatus to a location outside of the limits of the coin receptacle, such subsequent coin however in passing through such coin control apparatus actuating said coin-actuated member.

8. In combination, a casing having a coin-receiving slot therein, and also having therein a window for displaying an actuating coin; and coin control apparatus mounted within the casing adjacent said coin-receiving slot, said coin control apparatus including a coin-actuated member, means for transferring a coin entering the coin slot in a position at substantial right angles to the face of the casing to a position before said window in said casing in a plane substantially parallel to the casing face, means releasing before said window a previously inserted coin, and means providing, upon failure of a released coin to remove from said window, a passage for a subsequent coin from the coin control apparatus to a location outside of the same, such subsequent coin, however, in passing through such coin control apparatus actuating said coin-actuated member.
